FREE PISTON MACHINE

Raul Pateras Pescara, Neuilly sur Seine, France, assignor of three-tenths to Societe d'Etudes et de Participations Eau, Gaz, Electricite, Energie S. A., Geneva, Switzerland, a society of Switzerland

Original application February 16, 1939, Serial No. 256,751. Divided and this application February 26, 1940, Serial No. 320,950. In Luxembourg February 19, 1938

6 Claims. (Cl. 74—110)

The present application is a division of my copending application Serial No. 256,751 of February 16, 1939.

The invention relates to mechanisms for synchronizing the oppositely-reciprocating piston groups of a free piston machine, the pistons of which can have variable strokes.

It is known to connect the said reciprocating groups which are to be synchronized to the ends of oscillating levers by simple connecting rods, the levers generally being disposed on either side of the machine and being parallel in direction or crossed.

During the working of the machine, however, such structure produces inertia forces directed transverse to the direction of the displacements of the reciprocating groups, and, in the case of a machine provided with oscillating levers parallel to each other, creating an alternating torque which tends to produce an oscillation of the machine about a transverse axis. In the case of a machine having crossed oscillating levers, instantaneous torques are produced which tend to rotate the reciprocating groups about their axis.

The chief object of the present invention is to provide a mechanism of the type above described which is better adapted to meet the requirements of practice than present similar mechanisms and, in particular, free from the disadvantages above set forth.

According to the present invention, it consists of a kinematic mechanism, wherein the reactions transverse and particularly normal to the path of movements of the reciprocating parts are transmitted to a least one rigid element arranged in such manner as to be subjected simultaneously to the reactions of opposed direction, so as to balance them on said element.

Other features of the present invention will appear from the following detailed description of some specific embodiments thereof.

Preferred embodiments of the present invention will be described hereinafter, with reference to the accompanying drawings, given merely by way of example, in which—

Fig. 1 shows diagrammatically, in axial section, a free piston machine provided with synchronizing means made according to one embodiment of the invention;

Fig. 2 shows, in perspective view, the reciprocating parts of a free piston machine and the mechanism for synchronizing the movements of the reciprocating groups, the mechanism being made according to another embodiment of the invention; and

Fig. 3 shows, in transverse section, a modification of some of the elements of the synchronizing mechanism of Fig. 2.

In the following description, the invention will

be described as applied to a free piston machine made in any suitable conventional manner. For instance, as shown in Fig. 1, the machine is a motor-compressor including two motor pistons 1 and 1' adapted to slide in a cylinder 2, the wall of which is provided with inlet ports 3 and outlet ports 4 which are opened, respectively, by the pistons 1 and 1', when the latter are moving near to the ends of their outward strokes. Compressor pistons 5 and 5', respectively rigid with the pistons 1 and 1', are adapted to coat with compressor cylinders each provided with suction valves 6 or 6' and discharge valves 7 or 7'.

According to the invention, the means for synchronizing the displacements, in opposite directions, of the reciprocating parts or piston groups of the machine are arranged so that the normal reactions are transmitted to elements connected to the movable parts of said synchronizing means in such a manner that said elements are subjected to forces of equal intensities but opposed in direction so that they absorb these forces.

Referring to Fig. 1, the structure is devised in such manner that the normal reactions are balanced independently for each of the synchronizing mechanisms arranged on either side of the machine. This particularly permits the disturbing effects of these reactions to be eliminated, both when the synchronizing oscillating levers are parallel and when they are crossed.

In this embodiment of the invention, the displacements of the reciprocating parts of the machine are combined, in the known manner, by means of oscillating levers 18 which pivot about a fixed axis 8 and may either be parallel or crossed. The ends of these levers are connected to the reciprocating piston groups of the machine through connecting rods such as shown at 19 and 19' for the oscillating lever 18. It will be understood that only the parts on one side of the machine are shown in Fig. 1.

The pivots 20 and 20' of the connecting rods 19 and 19' located on the reciprocating pistons of the machine are connected, respectively, through connecting rods 21 and 21', to the ends of bell crank levers 22 and 22', mounted on fixed pivots 23 and 23'. The other ends of the bell crank levers 22 and 22' are linked, through rods 24 and 24' to toothed sectors 25 and 25' pivoted about fixed pivots 26 and 26' and having their respective teeth in mesh.

The various elements of this mechanism are arranged in such manner that the normal reactions R and R' (which are always in opposed directions) tend to turn the toothed sectors 25 and 25' in the same clockwise direction, so that the teeth of said sectors, being subjected to opposed forces of equal intensities, absorb these forces.

It will be readily understood that, when proceeding in the same manner for the pivoting systems located on the other side of the machine, a synchronizing device is obtained with which the reactions normal to the direction of the piston arrangements are transmitted to fixed elements, i. e. the toothed sectors in this case, so that they compensate one another and are thus eliminated.

The further embodiment which is illustrated by Fig. 2 concerns more particularly the case in which the synchronizing oscillating levers 18 and 18₁ are crossed. The device is arranged in such manner as to transmit to rigid elements capable of absorbing them, preferably by their resistance to twisting, the reactions of opposed directions which tend to produce rotations of the reciprocating parts of the machine about their axis. These reactions are reactions R and R₁ and reactions R' and R'₁ which, in consequence of this arrangement, become forces which compensate each other.

According to this particular embodiment of the invention, the reciprocating parts of the machine to be synchronized are connected to oscillating levers 18 and 18₁, respectively, through connecting rods 19, 19' and 19₁, 19'₁. The connecting rods corresponding to a reciprocating part of the machine may be pivoted either to the end of rods 27 and 27₁ rigid with the corresponding compressor piston, as shown on the left hand side of Fig. 2 or to the ends of a transverse bridge part 28', as shown on the right hand side of the figure.

The pivots of the connecting rods corresponding to the reciprocating part of the machine on the left of Fig. 2 are connected to an oscillating transverse bar 29 by rods 30 and 30₁. The pivots of the other connecting rods are connected to an oscillating transverse bar 29' by rods 30' and 30'₁, the rods 30, 30₁ and 30', 30'₁ being respectively connected to crank arms 31, 31₁, and 31', 31'₁, the first of which are rigidly carried by the bar 29 and the others by the bar 29'.

It will be readily understood that the reactions R and R₁ act on the bar 29 with opposed directions of rotation and that the bar will absorb said reactions by twisting. The same is true concerning the bar 29' and the reactions R' and R'₁.

Taking advantage of the fixing of the axes of the bars 29 and 29', it is possible to make use of the bars for introducing a cooling fluid or a lubricant into the reciprocating parts of the machine.

In particular, when the synchronizing connecting rods are pivoted to a bridge 28' rigid with a reciprocating part of the machine, the arrangement illustrated by Fig. 3 may be used.

In this arrangement, a conduit 32 for the feeding of a fluid such, for instance, as the cooling liquid, and a conduit 33 for the outflow of this liquid are respectively connected to the ends of the bar 29'.

In the bar 29', in the rods 30' and 30'₁, in the bridge piece 28' and in the reciprocating part in question, conduits 34 are provided which provide a circuit through which the cooling liquid can flow, packing means, such as shown at 35, being provided at the various joints of the mechanisms through which this circuit passes.

In all cases, whatever may be the particular embodiment that is chosen, the operation and advantages of the synchronizing device according to the present invention is sufficiently clear from the above description to make it unnecessary to enter into further explanations.

While the devices above described permit the reactions of the reciprocating parts of the machine normal to the direction of the piston displacements to be wholly eliminated, the invention also applies to cases in which these reactions are merely considerably reduced, in particular close to the extreme outer positions, where the inertia stresses are maximum.

While, in the above description, there has been disclosed what is deemed to be practical and efficient embodiments of the present invention, it should be well understood that the invention is not limited thereto as there might be changes in the arrangement, disposition and form of the parts without departing from the principle of the present invention as comprehended within the scope of the appended claims.

What I claim is:

1. In a machine including a frame and two parts reciprocating in opposed directions along a common longitudinal axis of movement with respect to said frame, a synchronizing device for synchronizing the opposite movements of said parts which comprises kinematic transmission means carried by said frame and interposed between said reciprocating parts, said synchronizing device producing opposed reactions transverse to said axis, at least one rigid member carried by said frame, and means separate from said transmission means for transmitting to said rigid member the opposed reactions.

2. In a machine including a frame and two parts reciprocating in opposed directions along a common longitudinal axis of movement with respect to said frame, a synchronizing device which comprises, in combination, at least one parallel lever pivoted to said frame about an axis perpendicular to said longitudinal axis, connecting rods extending between said reciprocating parts and the respective ends of said lever, two toothed elements rotatably carried by said frame and meshing together, and means for transmitting to said rotatable elements, respectively, the opposed reactions transverse to said axis, due to said synchronizing device.

3. A device according to claim 2 in which said rotatable members consist of toothed sectors operatively connected to said reciprocating parts.

4. In a machine including a frame and two parts reciprocating in opposed directions along a common longitudinal axis of movement with respect to said frame, a synchronizing device which comprises, in combination, two crossed levers pivoted to said frame on either side thereof about a common axis perpendicular to said longitudinal axis, connecting rods extending between said reciprocating parts and the respective ends of said levers, two bars journaled in said frame transversely to said longitudinal axis, crank arms rigidly fixed to each of said bars on either side of said longitudinal axis, substantially in the planes of movements of the respective oscillating levers, and connecting rods interposed between said crank arms and the reciprocating parts for transmitting to each of said bars opposed torsional stresses which are absorbed by said bar.

5. A device according to claim 4, in which said bars, crank arms and the last mentioned connecting rods are hollow so as to constitute conduits for a circulating fluid.

6. In a machine as claimed in claim 1, said kinematic transmission means comprising a lever pivoted about a fixed axis, and links connected to opposite ends of said lever and to said two parts.

RAUL PATERAS PESCARA.
